UNITED STATES PATENT OFFICE.

WILLIAM FREDRICK, OF TOLEDO, OHIO, ASSIGNOR TO R. C. FAULCONER,
TRUSTEE, OF DETROIT, MICHIGAN.

TYPE-WRITING MACHINE.

SPECIFICATION forming part of Letters Patent No. 570,546, dated November 3, 1896.

Application filed May 31, 1893. Serial No. 476,189. (No model.)

To all whom it may concern:

Be it known that I, WILLIAM FREDRICK, of Toledo, county of Lucas, and State of Ohio, have invented certain new and useful 5 Improvements in Type-Writers; and I do hereby declare that the following is a full, clear, and exact description of the invention, which will enable others skilled in the art to which it appertains to make and use the same, 10 reference being had to the accompanying drawings, and to the letters of reference marked thereon, which form part of this specification.

My invention relates to a type-writer of the 15 class known as "high-grade machines," in which both hands of the operator are employed in writing and the parts are all automatic with respect to the operation of the keys.

20 The object of the invention is to construct a machine of the character described that shall be of few parts and adjustments, and therefore inexpensive of construction, automatic in its movements, and positive in operation.

25 The invention consists generally in the peculiar construction of the various parts and their novel combination or arrangement, all of which will be fully illustrated in the drawings and pointed out in the claims.

30 The invention also consists especially in an improved automatically-shifting mechanism for reversing the feed of the ribbon, and also in an improved mechanism for holding the 35 hammer inert during the manipulation of the type-wheel, and then locking the wheel and releasing the hammer, which is spring impelled.

35 The invention relates also to a special construction for maintaining the type-wheel in its normal position, and relates also to a special construction of carriage whereby said carriage can be tilted back and moved to the right or left, as desired.

40 Figure 1 is a side elevation of a type-writer constructed in accordance with my invention. Fig. 2 is a longitudinal vertical sectional view through the machine. Fig. 3 is a rear 45 sectional elevation on lines X X, Fig. 1, illustrating more specifically the centering device for the type-wheel, the locking mechanism

for feeding the same, the feed for the carriage, and the springs for actuating the hammer. Fig. 4 is a sectional plan view of the machine on lines Y Y, Fig. 1. Fig. 5 is a 55 front elevation of the machine, the keys, levers, and a section of the front plate being broken away to show, respectively, the slots for guiding the levers and mechanism for feeding the ribbon, and the mechanism for 60 reversing the feed of the same. Fig. 6 is a side elevation of a portion of the machine, said view being partly broken away to show the mechanism for projecting the hammer. Fig. 7 is a plan view of a portion of the 65 machine illustrating the ribbon-spools, the type-wheel, and a part of the mechanism for reversing the feed of the ribbon. Fig. 8 is a detail elevation of the alarm mechanism. Fig. 9 is a perspective view of the type-wheel, 70 showing the form of the same. Fig. 10 is a detail view of a modified form of mechanism for securing tension upon the hammer.

1 designates the frame of the machine, in the side plates 2 of which is journaled the 75 rock-shaft 3 of the torsional or twisted rocking bars or frame 4. Said bars or frame extend substantially parallel with the rock-shaft and are inversely inclined, and are secured to the rock-shaft at each end. At a 80 point substantially midway the length of the rock-shaft 3 is secured the lower end of an arm 5, having arms 6 projecting therefrom, circular at their outer ends to embrace the torsional rocking bars 4, and secured thereto 85 preferably by soldering.

7 designates a segmental rack-bar integral with arm 5, and at its upper end the said rack-bar, engaging with a pinion 8, secured upon a tubular shaft 9, journaled in a similar shaft 90 9', secured in a casting 92, extending downwardly from the under surface of the frame.

Loosely journaled in the bore of the tube is a solid shaft 10, upon the upper end of which is secured, in any preferred manner, 95 the type-wheel 11, the lower end of the shaft extending through pinion 8 and below the same, and formed with a rounded lower end, against which abuts the rear end of an arm 12, secured upon a shaft 13, journaled at each 100 end in the sides 2 of the frame, the shaft and type-wheel being raised by means of a key-

lever 13', the rear end of the same being fixedly secured to the shaft 13 with reference to rotative movement, but pivotally secured with relation to lateral movement, the lever 5 passing through a stepped opening 14' in the front plate of the frame, the shoulder 14' limiting the movement, so that the shaft and arm 12 are only rocked to raise the type-wheel to present the second row of type-characters, 10 which comprise the capital letters, and the shoulder or base of the opening 14' limiting the movement of the raise of the type-wheel to present the lower row of characters, which comprise the numerals, punctuation-marks, 15 &c., there being a spring 15, secured at one end to a pin 16, in the front plate 17 of the frame, the spring exerting at all times an upward pull upon the key-lever 13', which results in a downward movement of the arm 12, 20 the gravity of the shaft 10 and the type-wheel 11 causing the lower end of the shaft to abut at all times against the lever.

Type-wheel 11 is preferably formed of a shell 11', of vulcanized rubber, aluminium, or 25 analogous material, having vertical recesses 11' therein, the type-faces 11' being preferably cast thereon, the object being to secure lightness, thereby preventing too great momentum as the wheel is rapidly revolved.

30 Secured upon the upper end of tubular shaft 9 is a cross-piece forming arms 18, there being projections 19 upon the ends of the same, which enter recesses 11' in the type-wheel to revolve the wheel, it being understood that 35 the type-wheel can be raised or lowered independent of the mechanism for revolving the same, and at the same time revolves therewith.

21 designates a notched wheel secured upon 40 revoluble tubular shaft 9, and revolves therewith, the notched wheel having as many notches or recesses in the periphery as there are type-faces in a row around the wheel, there being a pawl-faced arm 23 of a size and 45 shape to enter the recesses, said arm being secured in a shaft 28 and rotating therewith to engage the notched wheel to lock the type-wheel in position.

29 designates shaft parallel with shaft 28 50 and journaled in the sides 2 of the frame, and upon said shaft near each end are secured levers 30 and 30', the forward ends of the levers extending to near the front of the machine, and connected by means of a hollow 55 revoluble shaft 31, journaled at each end on said levers, thus forming a spacing-bail, there being a screw-threaded rod 31' secured into and extending in the rear of the shaft, upon which is an adjustable weight 31', which 60 serves to normally raise shaft 31. If desired, however, a spring may be interposed between the frame and levers 30 and 30' to subserve the purpose of the weight.

32 designates key-levers, the rear end of 65 which have a notch 32' upon the upper edge, which engages with the upper side of slots 33 cut in the back of plate 34 of the frame,

the front ends of the levers passing through slots 35 in front of plate 17, where the keys 35' are secured thereto.

36 designates spring-arms integral with plates 36', which are riveted to cross-piece 34', the arms bearing against the key-levers to normally raise the same.

32' designates space-levers similar to key-levers 32, the slots 33' being shorter to give a shorter stroke to the same, so as to allow the space-bar to operate without moving the type-wheel-operating shaft, the space-levers being connected by a space-bar 32'', extending across 80 the front of the machine.

37 designates an arm loosely journaled at one end upon shaft 28, the opposite end having a slot 38 therein, into which passes a pin 39 upon arm 30.

40 designates a coiled spring, one end being attached to a hub 41, secured upon shaft 28, the opposite end secured to a ratchet-wheel 37', loosely secured to the shaft, there being a pawl 37' secured to the arm 37 and 90 engaging with the teeth of the ratchet-wheel, by which means, when the wheel is revolved, the spring is regulated, there being a pin 37'' in shaft 28, which strikes a projection 37''' to limit the movement of the shaft.

42 designates a gravity-catch having a recess or notch 42' therein, in which engages a pin 42'', secured to shaft 28 on the opposite end of the shaft to that occupied by pin 37'', already described, the catch being disengaged 100 from the pin by means of projection 42''' upon lever 30, the catch automatically engaging the pin.

43 designates the paper-carriage, comprising a paper-receptacle 44, formed substantially circular in cross-section, having an opening 44', into which the paper is inserted.

45 designates the feed-roller, journaled in the carriage, and preferably formed with a rubber or analogous covering, revolved by 110 hand-knob 45'.

46 designates a friction - roller bearing against the feed-roller, said roller being journaled in openings 46' in the carriage, and held against the feed-roller by means of 115 springs 47, secured to the carriage and bearing against the friction-roller.

48 designates a guide-rod secured in the carriage to guide the paper and hold the same 120 in position to receive the impression.

Rear plate 34 of the frame extends forwardly as a covering for the rear end of the type-bars, &c., and is turned at an angle, forming a downwardly-projecting end 34', on which is journaled antifriction-rollers 49, 125 upon which rides a shaft 50, secured in the carriage, the shaft being held on the antifriction-rollers by clamp 51, secured to the frame and passing over the shaft.

52 designates a ratchet-bar secured to the 130 lower side of the paper-carriage, the teeth of the bar normally bearing against a pawl 52' when tension is given to the carriage to move the carriage by means of flexible connection

53, connecting the carriage and a spring-actuated drum 54, said pawl being secured to the shaft 29 and rocking with the same. Pivoted to the pawl at 55 is a weighted movable pawl 56, which has a movement equal to the distance between the teeth on the ratchet-bar, so that when shaft 29 is rocked and the ratchet-bar engages the movable pawl the carriage moves forward the distance of one notch, and when the shaft is reversed the pawl 52' engages the teeth and the movable pawl swings back by its gravity one notch, and the operation is repeated, and the carriage moves forward.

15 It will be seen that in tilting the carriage it swings upon the shaft 50 and disengages from the pawls 52' and 56, and the carriage is free to be moved laterally in either direction.

57 designates tubular bearings secured to the under side of top plate 22 and extending downwardly therefrom, in which are journaled pins 58, having secured upon the upper squared ends thereof ribbon-spools 59, having a ribbon 60 passing from one spool to the other in either direction as they are unreeled.

61 designates a U-shaped lever pivoted to the upper face of the top plate midway of the spools, the bend of the lever being against the coil of ribbon on the spools, the arms moving from side to side as the spools are unreeled and reeled. Midway of the arms projects an arm 63 of a weighted lever 64, said lever being pivoted at the lower end on a pin 17', fixedly secured to the inside of the front plate 17 by a screw 17² passed through the front plate and screwing into the pin 17', the upper end moving in the arc of a circle and actuated by the arms of the U-shaped lever 61 moving the lever to beyond the vertical center, the weight serving to throw the same to the opposite side.

In the body of the lever 64 is a slot 65, in which projects one end of a pin 66, the pin being secured in a double reversible pawl 67, which is pivoted to one arm of a bell-crank lever 68, which is oscillated by means of the arm 69, the arm being connected to the lever 30' by a link 30². Secured upon the lower ends of pins 58 are ratchet-wheels 71, having upwardly-extending teeth with which contact one of the ends of a double pawl 67, the teeth being arranged to revolve by a downward movement of the space-rod and held from backward movement by a double catch 67'.

55 72 designates an inclosing shell or case for the type-wheel, having a cut-out portion of a size to admit of the hammer contacting with the type-faces in line therewith, (see Fig. 7,) and over which the ribbon passes, the shell 60 or case serving to form a protection for the type, not only to keep the ribbon from rubbing against the same, but to exclude dust from the type-wheel.

Secured to shaft 28, substantially midway the length of the same, is lever 73, which passes through a slot in the horizontal portion of the rear plate 34 of the frame and upwardly

to a point opposite the upper row of type on the type-wheel, at which point is secured the hammer 74, having a perforation therein, in 70 which is inserted a rubber or metal pounding-face 74', which serves to make a good impression of the type, as the rubber yields to the face of the same. If desired, however, a solid hammer may be employed and a rubber band 75 74², or analogous material, placed between the hammer and type-wheel, as shown in dotted lines, Fig. 2.

Secured upon guide 48 is an adjustable stop 75 for the hammer when placed at any desired position, but used more specifically at the end of the line, prevents the hammer from striking over or piling up letters after the carriage has reached the limit of its movement, there being a bell 75' secured upon the stop, 80 having a hammer 75², the opposite end of the hammer extending beyond the stop 75 in a position to be slightly raised to sound the alarm as the hammer in passing under raises the same.

90 As the characters entirely surround the type-wheel 11, to alternately use a character at or near the extreme limit of one revolution of the same, the character at or near the limit of the opposite revolution of the same in succession, requires the type-wheel to have a substantially complete revolution, which increases the momentum. To secure a partial revolution of the same and only a minimum momentum, I provide for only a half-revolution as the extreme limit of the movement by forming a pin 76 on the lever 5 in the transverse center of the same, to which one end of a spring 77 is secured, the opposite end being secured to the under side of the top plate, 100 the tension of the spring normally drawing the lever 5 to a vertical position and at all times normally holding the type-wheel in position to cause the characters composing each half of the turn to be equally divided, so that 110 the type-wheel is only revolved one-half a revolution in either direction at the farthest, and automatically returns to the original position.

78 designates a supplemental guide for the paper as it is fed from the paper-holder, which not only holds the paper so that the matter printed thereon is visible to the operator, but keeps the paper from contact with the hammer and spring-actuated drum 54, said supplemental guide being adapted to fold over the front of the machine, as shown in dotted lines, Fig. 1, to admit of a cover inclosing the type-writer.

78' designates a copy-holder comprising inclined standards 79, the lower ends of which are secured in a foot 80, which is secured in the frame of the machine, there being a clamp 81 upon the upper side of the copy, it being understood that the holder extends above the 125 frame a sufficient distance to hold the copy above the carriage and paper as it is fed therefrom, so that it is plainly visible to the operator.

In operation the paper is first inserted into the paper-carrier by passing the same between feed and friction rollers 45 and 46 respectively, the paper rolling up in the cylinder 44 until only the end is visible, and in position between the type-wheel and hammer, the carriage being pulled to the side of the machine. A key is now depressed by the operator, lowering one of the key-levers 32 which first alines the torsional rocking levers with the under side of the same, rocking shaft 3, lever 5, segmental gear 7, turning-gear 8, shell 9, arms 19, and type-wheel 11, a sufficient distance to aline the type-faces represented by the key depressed. The key-lever has now been depressed to a degree to lower shaft 31 a sufficient distance to rock lever 30 sufficiently to depress arm 37 to put tension upon spring 40, shaft 28 remaining stationary, owing to the catch 42' engaging the pin 42², until when the key-lever has been fully lowered the catch is released from the pin 42², the spring now revolving shaft 28, first causing pawl-arm 23 to revolve to engage with the pawl-wheel holding the type-wheel in a locked position. The hammer is now projected and the impression of the type-face is now made upon the paper interposed between the same. The key is now released and the spring 36 returns the key-lever to its original position, the weighted rear ends of levers 30 and 30' returning shaft 29, the pawl-arm 23 and hammer 74 being retracted and resuming the original position, the spring 77 returning the type-wheel to its normal position, and the carriage is moved the distance equal to one notch in the ratchet-bar 52, ready for a repeated operation. As a key, and consequently the lever 30', is depressed the bell-crank lever 68 is rocked, oscillating the double pawl 67, which engages one of the ratchets in wheel 71 and revolves the same, the direction of the feed being regulated by the U-shaped lever 61, as has been described, the double catch being also operated by the U-shaped lever 61 and at all times keeps the ribbon from reverse motion.

To make a space between each word, the space-bar is depressed, which lowers the levers 30 and 30' to rock shaft 29 to a degree (their movement being limited in its downward direction by contacting with the lower wall of the short slots 33') to engage the movable pawl with the ratchet-bar of the carriage, which allows the same to move forward the required space. As a line is completed, the carriage is tilted back, releasing the rack-bar from the pawls, and is now free to be moved to the opposite side of the machine to commence a new line.

In the modified construction shown in Fig. 10 lever 37 on shaft 28 is formed with an arm 38', connected with pin 42² by means of a coiled spring 28³, and lever 37 is connected with arm 30 by means of a link 30³, the catch 42 in this instance operating to control the end of pin 38². In this construction spring 40 and connections are omitted, it only being necessary to raise or lower spring 28³ to secure greater or less tension upon the same.

While I have shown three rows of type upon the type-wheel, I may use any number of rows of type, the operation being the same.

It will be seen that, by means of the hammer being projected by the spring, the tension of which is set to the same point for each stroke, I produce an even pound upon the same, thereby making an even impression of all characters upon the paper.

In manifolding, the rubber inserted in the hammer is removed, the solid hammer is inserted, by which operation a harder stroke is given, and the manifolding perfected.

While I have shown and described anti-friction-rollers upon which the paper-carriage moves, I also wish it understood that any other means may be employed.

What I claim is—

1. In a type-writer, the case and key-levers, a rock-shaft journaled in the case, a frame rigidly connected with said rock-shaft and adapted to be operated upon by the key-levers, said frame comprising longitudinal bars parallel with the rock-shaft upon opposite sides of the same and connected thereto at each end, said bars being inclined with reference to their length, each bar having an opposite inclination, a vertical arm secured to the rock-shaft and each longitudinal bar and carrying a segmental tooth-bar upon its upper end and a type-wheel having a shaft provided with a pinion adapted to mesh with the segmental tooth-bar.

2. In a type-writer, the type-wheel, and ribbon-spools, the ratchet-wheels connected with said spools, a double reversible pawl pivoted between the ratchet-wheels, a weighted lever connected with the reversible pawl, a U-shaped lever pivoted between the spools and adapted to contact therewith, an elbow-lever pivotally connected with the pawl, the spacing-bail and the link connecting the elbow-lever and spacing-bail.

3. In a type-writer, a type-wheel and shaft, and means for operating the same, a notched wheel mounted upon the end of the type-wheel shaft, a spring-actuated hammer-shaft, a hammer carried thereon, and a locking-arm also carried by said shaft and in advance of the hammer, adapted to engage the notched wheel prior to the stroke of the hammer, and thus hold the type-wheel rigid during said stroke.

4. In a type-writer, a type-wheel and means for operating the same through the medium of a series of keys and key-levers, a hammer-shaft, a hammer carried thereby, a spring for driving the hammer, a shaft parallel to said hammer-shaft carrying levers 30 and 30' having a shaft 31 secured to the ends of the same, said shaft normally bearing against the under side of the key-levers, a lever 37 connecting the lever 30 and a ratchet-wheel 37' upon the hammer-shaft, a pin 42² projecting downwardly from the hammer-shaft normally in

engagement with a lever 42 and a pin carried by the lever 30' in the path of travel of lever 42, whereby when a key-lever is depressed the type-wheel is first revolved and tension 5 put upon the spring and the lever 42 is then depressed releasing the hammer-shaft and allowing it to be projected under the action of the spring.

5. In a type-writer, a case and a rock-shaft 10 arranged therein below the key-levers, a segmental toothed arm connected with and operated by said shaft, the type-wheel and shaft, said shaft carrying a gear adapted to mesh with the toothed arm and a spring connected 15 with the toothed arm at one end and to the case whereby the tension of the spring is to normally hold the arm in alinement with the spring or the segment in an intermediate position as regards the pinion.
- 20 6. In a type-writer, the ribbon-spool carrying ratchet-wheels upon the lower ends of the

shafts, a double pawl, a lever for shifting said pawl to reverse the ribbon-feed, said lever having an arm extending above the pawl, and a U-shaped lever pivoted between the ribbon-spool, and adapted to alternately contact therewith, whereby as one spool is filled the U-shaped lever is moved, operating the arm of the lever and reversing the movement of the pawl.

7. In a type-writer, a guide for the paper, a stop for the hammer adjustable thereon, a bell, the hammer-lever of which is in the path of travel of the impression-hammer to raise the same.

In testimony that I claim the foregoing as my own I hereby affix my signature in presence of two witnesses.

WILLIAM FREDRICK.
